Inventor

A. Judson

UNITED STATES PATENT OFFICE.

A. JUDSON, OF UNADILLA, NEW YORK.

CONSTRUCTION OF CANAL-BOATS.

Specification of Letters Patent No. 21,201, dated August 17, 1858.

To all whom it may concern:

Be it known that I, ANSON JUDSON, of the town of Unadilla and county of Otsego and State of New York, have invented a new and useful Improvement in the Construction of Canal-Boats to be Propelled by Steam or other Power; and I do hereby declare that the following is a full, clear, and exact description of the same, reference being had 5 to accompanying drawing and letters of reference marked thereon and making a part of this specification.

Figure 1st is a cross section showing the plan of a boat constructed of wood or iron, 15 or partly of wood and partly of iron straight on the bottom and of a size adapted to the canal and locks where used. A, is a square tube extending longitudinally from stem to stern and as large in diameter as one-fourth 20 the width of the boat or thereabout. The bottom of the boat forms the lower section or partition of said tube, see end views Figs. 3 and 4.

Fig. 1st is a straight continuation of said 25 tube and forming a part of the outer and lower bottom of said boat from stem to stern and in connection with the sides of said tube forms a funnel shaped aperture at either end

for the ingress and egress of the water equal to the path of the boat in its passage through 30 the water.

Fig. 2nd: F, is a cope formed by the extension of the top of the tube as indicated by the dotted line, G, to aid in concentrating the water in its ingress and egress to and from said tube and to prevent the escape of 35 the water from said tube by the action of the wheel.

Having thus fully described a boat to be 40 propelled by steam or other power on canals I now set forth my claim.

I do not claim the tube for the ingress and egress of the water through said boat as a motive or propelling power or the use of the wheel as described to force the water 45 through said tube. But

What I claim and desire to secure by Letters Patent is—

The wide opening in the bow and stern of the boat extending to or near the full width 50 of the boat and as low as the bottom substantially as and for the purposes described.

ANSON JUDSON.
